DESIGN FOR A CONVERTIBLE TROUSER-SKIRT

Ethel Eaton Stricker, New York, N. Y.

Application April 7, 1942, Serial No. 106,482

Term of patent 3½ years

To all whom it may concern:

Be it known that I, Ethel Eaton Stricker, a citizen of the United States, residing in New York city, in the county of New York and State of New York, have invented a new, original, and ornamental Design for a Convertible Trouser-Skirt, of which the following is a specification, reference being had to the accompanying drawings, forming part thereof.

Fig. 1 is a front view of a convertible trouser-skirt showing my design with the front panel members partially unfastened and turned back;

Fig. 2 is a rear view of the convertible trouser-skirt shown in Fig. 1 with the rear panel members partially unfastened and turned back;

Fig. 3 is an enlarged fragmentary side view of the convertible trouser-skirt shown in Fig. 1 with one of the front and rear panels in unfastened and turned back position;

Fig. 4 is a similar view of the garment shown in Fig. 3, showing the front and rear panels partially fastened together in converted position;

Fig. 5 is a front view of the convertible trouser-skirt shown in Fig. 1 in converted position; and

Fig. 6 is a rear view of the convertible trouser-skirt shown in Fig. 1 in converted position.

I claim:

The ornamental design for a convertible trouser-skirt, substantially as shown and described.

ETHEL EATON STRICKER.
